John Rogers.

DES. 1936

John Rogers of New York, N.Y.
Letters Patent No. 1936-Dated April 19th 1864.
Design for a Group of Figures.

The schedule referred to in these Letters Patent and making part of the same.

To all whom it may concern:

Be it known that I, John Rogers, of the City of New York, in the County and State of New York, have invented or produced a new and original design for a group of figures; and I do hereby declare that the following is a full and exact description of the same.

The group consists of three figures and is called the "Union Refugees." It is composed of a man carrying a gun over his right shoulder. A woman rests against him on his left, while a boy on her left is putting flowers into her hand, all of which are clearly seen in the accompanying drawings.

What I claim as my invention or production, and desire to secure by Letters Patent is,

The design for a group of figures as shown and described.
